UNITED STATES PATENT OFFICE.

FRITZ HELLER AND ADOLF HARTEL, OF KASNIAU, NEAR PILSEN, CZECHO-SLOVAKIA.

DEVICE FOR REMOVING ASHES FROM PRODUCERS.

1,363,116.

Specification of Letters Patent. Patented Dec. 21, 1920.

Application filed October 7, 1920. Serial No. 415,448.

To all whom it may concern:

Be it known that we, FRITZ HELLER and ADOLF HARTEL, citizens of the Republic of Czecho-Slovakia, and residing at Kasniau, 5 near Pilsen, Czecho-Slovakia, have invented certain new and useful Improvements in Devices for Removing Ashes from Producers, of which the following is a specification.

- 10 This invention relates to a device for automatically removing ashes from producers which have no grates and in which an ash-pit terminates in horizontal gutter-shaped troughs. By this invention there is 15 mounted in each gutter at the end, opposite the discharge opening, a flap, pivoted or hinged on a horizontal axis at the end of the ash-pit, which oscillates in the longitudinal direction of the trough and thereby 20 pushes the column of ashes in the said direction.

In the accompanying drawing Figure 1 shows a vertical section of the lower part of a gas producer constructed without a 25 grate, together with the automatic device for removing the ashes. Fig. 2 is a section on line A—B of Fig. 1.

In continuation of the lower end of the ash-pit *a* is an iron casting *b* containing 30 gutters which open, as at *c*, into a conveyer trough *d*. The rear portion of each gutter is constructed as a kind of casing for the flap which is to forward the ashes which have collected in the gutter. The flap or 35 tongue *f*, arranged at the end opposite the discharge opening, is adapted to oscillate on an axis *g* at the end of the ash-pit under action of a rod *h* and crank *i* on a shaft *n*. As shown the crank mechanism is arranged 40 at the rear side of the flap *f*. The ashes in the gutter in front of the flap *f* are pushed

forward at every forward movement of the flap toward the conveyer trough *d*. As the flap performs its backward movement a further quantity of ashes falls from the ash- 45 pit as the gasification of the coal in the contracted chamber *k* proceeds in front of the nozzles *m*.

The conduit and gutters are adapted to contain water to form with the flaps an air 50 seal at the bottom of the producer.

In consequence of the distribution of the ashes among several streams corresponding with the number of the gutters and the provision of a flap operating in each a uniform 55 removal of the ashes is obtained.

We claim:

The combination with a grateless producer having an open lower end, of a plurality of parallel gutters arranged below the 60 lower end of said producer adapted to contain water and having curved surfaces at one side of the producer, a discharge conduit arranged at an angle to said gutters, 65 adapted to contain water and communicating with the latter, a conveyer located in the discharge conduit, a pivotally mounted flap located at the curved end of each gutter and having its pivot located at the axis of curvature of the gutter, a crank shaft provided 70 with a number of crank portions, and connecting rods coupling the rear portions of said flaps to the crank portions of the shaft, whereby rotation of said shaft will cause 75 said flaps to oscillate in the curved portions of the gutters to force ashes along the gutters without permitting the entrance of air into the gutters.

In testimony whereof we have affixed our signatures.

FRITZ HELLER.
ADOLF HARTEL.
